[57] CLAIM

The ornamental design for a toner container, substantially as shown.

DESCRIPTION

FIG. 1 is a front perspective view of a toner container showing our new design;

FIG. 2 is a side elevational view;

FIG. 3 is a side elevation view showing the side opposite that shown in FIG. 2;

FIG. 4 is a top plan view;

FIG. 5 is a bottom plan view;

FIG. 6 is a front elevational view; and

FIG. 7 is a rear elevational view thereof.
